Fig. 8. Charles S. Macdonald, INVENTOR

By *Charles L. Morris*
ATTORNEY

UNITED STATES PATENT OFFICE

CHARLES SIDNEY MACDONALD, OF LONDON, ENGLAND

MECHANISM OF SAXOPHONES

Application filed April 26, 1926, Serial No. 104,766, and in Great Britain August 21, 1925.

This invention relates to improvements in saxophones and like wind instruments in which vents are closed or opened by the movements of tampions operated by keys so as to close and open the vents in different combinations and thus to cause the instrument to sound the required notes.

The said invention comprises means whereby movement of selected tampions causes simultaneous movement of other tampions so that by operating only a single key two or more of the tampions may be moved to the open or closed position in a predetermined combination. The improved means for coupling the tampions so as to cause them to move simultaneously, can be advantageously applied to the tampions of vents opened to produce notes at the upper end of the compass of the instrument, and by means of this invention the tampions of selected groups of vents can be coupled so that when any vent in the selected group is opened, the vents below it, i. e. nearer to the bell of the instrument, and comprised in the same group, are also opened. Similarly the tampions can be coupled so that when any vent in a selected group is closed, the vents above it, i. e. nearer the mouth-piece, and comprised in the same group, are also closed.

The accompanying drawings show how the said invention can be conveniently and advantageously carried into practice. In this drawing:—

Figure 1 is a part of the tube of the instrument developed or opened out to show flatly the tampions, keys and connections arranged in accordance with this invention, omitting some of the keys and connections which are not affected by the improvements herein described.

Figure 2 shows an arrangement similar to that of Figure 1, provided with an additional tampion and key in the upper register.

Figures 3, 4 and 5 respectively show modified arrangements of some of the keys of the instrument illustrated in Figure 1.

Figures 6, 7 and 8 respectively illustrate a modified arrangement of the tampions and keys suitable for an instrument in which the

vents of the upper notes are arranged in a straight line.

Figure 9 illustrates an arrangement hereinafter described.

Referring to Figure 1, a series of tampions, indicated by the numerals 1 to 13 inclusive, are provided respectively covering the vents of the instrument, the tampion 1 being nearest to the mouth-piece. Each of the tampions is acted upon by a spring in the usual manner, the tampion 1 being a closed tampion which can be opened by means of a barrel arm 14, barrel 15 and key 16. The tampion 2 is a closed tampion opened by a key 17 or alternatively it can be opened by a lever 18 carried on a barrel 19 and moved to raise the tampion 2 by a bar 20 and key 21. The key 21 is an additional key enabling the tampion 2 to be opened by right hand fingering as well as by left hand fingering. The tampion 3 is opened by means of a spring but is normally held closed by a barrel arm 22 raised by a stronger spring, and depressed to allow the tampion 3 to open by means of a key 23 pressed against the said arm 22. The key 23 is carried on a barrel 24 movable independently of the barrel 25 carrying the tampion 3. The barrel arm 22 is mounted on a barrel 26 carrying an arm 27 depressed by an arm 28 on a barrel 29 from which a second arm 30 projects above a key-lever 31 so that when this key lever is depressed the barrel arm 22 is likewise depressed to allow the tampion 3 to open. Thus means are provided for opening the tampion 3 alone either by a finger of the right hand or a finger of the left hand.

The barrel arm 22 extends below and in contact with the key 17 so that when the tampion 2 is opened the tampion 3 opens simultaneously. Moreover the lever 18 extends below the tampion lever 1 so that when the tampion 1 is opened by the key 16, the tampions 2 and 3 are simultaneously opened.

The tampion 4 is an open tampion carried on a barrel 32 supporting a bar 33 having an arm 34 which extends below and in contact with the lever of a key 35, so that when the key 35 is depressed the tampion 4 is closed. The tampion 5 is closed by a key 36 and the lever of this tampion extends under the bar

33 to also close the tampion 4. The tampion 6 is closed by a petal key 6^a, by the key 35 or by a bar 38 carried on a barrel 39 having an arm 40 projecting below a coupler 41 projecting from the tampion 10 which is closed whenever any one of the tampions 11, 12, 13 are closed, the levers of the tampions extending below a bar 42 extending to the barrel 43 of the tampion 10. The tampion 7 is closed by the key 35 mounted on the same barrel.

When either of the tampions 4, 5 or 7 is closed the bar 33 is rocked so that the arm 34 depresses an arm of a lever 44 carried on a barrel 45 and arranged so that if the tampion 3 is open when either of the tampions 4, 5 or 7 close, the lever 44 will move the tampion 3 to its closed position, but when the tampions 4 and 5 are opened the lever 44 does not obstruct the opening movement of the tampion 3. On depressing the tampion 6 a coupler 46 acts similarly on the lever 44 to close the tampion 3. As above mentioned, the tampion 6 can be closed by the keys 6^a, 35 or by the keys of one of the tampions 11, 12, 13 so that the tampion 3 can be held closed by fingers of the right hand or of the left hand, as most convenient.

When the invention is applied to a saxophone, the tampion 1 may correspond to the top E $\frac{1}{2}$ vent, the tampion 2 to the top E $\frac{1}{2}$ vent and the tampion 3 to the top D $\frac{1}{2}$ vent. Then, when the key 16 is depressed the E $\frac{1}{2}$, E $\frac{1}{2}$ and D $\frac{1}{2}$ vents open simultaneously thus providing for the fingering of top E $\frac{1}{2}$ by the depression of one key alone instead of requiring the depression of three separate keys. By depressing either the key 21 or the key 17 the E $\frac{1}{2}$ and D $\frac{1}{2}$ vents are opened, and by depressing either the key 23 or key 31 the D $\frac{1}{2}$ vent alone is opened.

Whilst additional means for fingering some of the notes are thus provided, each of these notes can still, if required, be fingered in the usual manner as on instruments as heretofore constructed. Moreover by means of the barrel lever 44 when the vents for sounding C $\sharp$, C $\sharp$ B $\frac{1}{2}$ and B $\frac{1}{2}$ are closed, the D $\frac{1}{2}$ is also closed.

In the modified arrangement illustrated in Figure 2, an additional tampion 47 is provided nearer to the mouthpiece of the instrument than the tampion 1. In this case the tampion 47 which is a closed tampion carried on a barrel 48, can be opened by depressing its key 49 and then moves a lever 50 by means of a coupler 51 to open the tampions 1 and 2 and consequently the tampion 3. The lever 50 passes above the tampion lever 1 so that this tampion can be opened by depressing the key 16 acting through the barrel 15 and barrel arm 52. The lever 50 then opens the tampions 1, 2 and 3 without opening the tampion 47, the lever 50 passing below a bridge in the lever of this tampion. The rest of the keys in this arrangement are disposed, for example, in a similar manner to the corresponding parts in

Figure 1, or, as shown in Figure 2, in which the alternative key 21 of the tampion 2 is omitted. Also, in Figure 2 the barrel 29 is moved by a lever on the barrel of tampion 13 so that the key 31 is dispensed with, the tampions 11 and 12 moving the bar 42^a for closing the tampion 6.

The lever 44^a, comprising two arms carried on a barrel 45^a, takes the place of the lever 44 in Figure 1, and extends below the key 36 and the petal key 6^a, a bar 33^a being arranged to extend above the lever of the key 35 for closing the tampion 4. In this case also the lever 44^a supports the lever of tampion 3 whenever any of the tampions 4, 5, 6 or 7 is closed. The key 49 is carried clear of the lever 44. Obviously the arrangements of the levers 44 and 44^a are interchangeable.

A modified arrangement of the key 35 of Figure 1 is shown at 35^a in Figure 3 in which the lever of this key acts on an extension 53 of the bar 33 instead of acting on the arm 34.

In the arrangement shown in Figure 4, a bar 54 extends below the levers of the tampions 5 and 6, so as to be depressed by the closing of either of the said tampions whereby an arm 55 acting on the lever 44 causes the simultaneous closing of the tampion 3.

In place of the arm 22 for holding the tampion 3 closed, the barrel 24, Figure 5, may be provided with a sufficiently strong spring. The finger key 23 is then provided with arms 56, 57, respectively extending above the levers of the tampions 2, 3. Then, when the key 23 is depressed the tampion 3 is opened by a spring, and when the key is released the tampion is closed by the spring of the key which is stronger than the tampion spring. The lifting of the arm 56 does not affect the tampion 2 but when the key 17 is depressed the tampion 2 in opening raises the arm 56 and permits the tampion 3 to open.

The improved means for coupling the tampions so as to move simultaneously can be adapted to instruments in which the vents of the high notes are arranged in a straight line. In Figure 6, the top tampion 47 is opened by a key 49 opening in succession the tampion 1 by the coupler 58 which opens the tampion 2 by the coupler 59. The key 17 of the tampion 2 depresses a key 23 which in turn depresses an arm 22 thrust upwardly by a stronger spring than that operating to open the tampion 3. When the thrust of the arm 22 is removed the tampion 3 opens. The tampion 1 lifted by the key 16 leaves the tampion 47 closed and opens tampions 2 and 3 also. The key 17 opens tampions 2 and 3 whilst the key 23 opens tampion 3 only.

The tampion 4 in Figure 6 is closed by a key 35^a acting through a bar 33 which is raised when the key is depressed, this bar being also raised by the depression of either of the tampions 5 or 6. The closing of the tampions 5 or 6 separately or together closes

130

the tampion 3 by depressing an arm 60 on the barrel 61 carrying the said tampion 3.

A modification of the arrangement last described is illustrated in Figure 7 in which 5 the key 23 rests on the tampion 3 at 62 but is not otherwise connected to it. When the key 23 is lifted off the tampion 3 the latter is raised by a spring. The lever of the tampion 3 is connected by a bar 63 to an arm 64. On 10 closing the tampion 4 the arm of the bar 33 closes the tampion 3; the tampions 5 and 6 close the tampion 3 by pressing down the arm 64 of the bar 63. A coupler 65 on the tampion 4, Figure 8, closes the tampion 3; the 15 tampion 5 acts through the bar 33 to close the tampions 4 and 3.

The key lever 31 may be arranged to extend under the key of the tampion 13 so that by closing the tampion 13 the tampion 3 is 20 opened but the lever 31 can be depressed alone as shown in Figure 9.

While the keys for playing any of the notes from middle E to upper C are being operated, the fingering for the top D can be 25 held by the keys 31 or 23, the vent opening when the keys for sounding the group E to C are released. If C $\sharp$ occurs in any passage whilst the fingering for top D is held in the manner above mentioned, C $\sharp$ may be fingered 30 by depressing one of the keys 11 or 12 to close the tampion 6, or by closing this tampion by direct fingering, whereby the tampion 3 is also closed.

As a further example, middle D $\natural$ and its 35 octave above, middle D $\sharp$ and again the upper D $\natural$ may be executed by holding the key 17 throughout the passage.

The shake on top C $\sharp$, D $\sharp$ is executed by holding the fingering for top C $\sharp$ and shaking 40 key 17 (or 21 in Figure 1). The shake D $\natural$, E $\natural$ is executed by holding the fingering for D $\natural$ and shaking key 16. The shake E $\flat$, F $\flat$ is executed by holding fingering for E $\flat$ by 45 key 17 and shaking key 49.

45 I claim:—

1. A saxophone or like musical instrument comprising a series of key operated tampions for opening and closing vents corresponding to a group of successive notes of the chromatic 50 scale arranged so that the tampions of the upper notes are normally closed and the tampions of the lower notes are normally open, having in combination therewith a spring urged barrel arm which is rocked when any 55 of the upper note tampions is opened to allow the lowest normally closed tampion to open and a lever moved when any of the lower note tampions is closed cooperating with said barrel arm to positively close the said lowest normally 60 closed tampion.

2. A saxophone or like musical instrument comprising a series of key operated tampions for opening and closing vents corresponding to a group of successive notes of the chromatic 65 scale arranged so that the tampions of the upper

notes are normally closed and the tampions of the lower notes are normally open, a weak spring for holding the lowest normally closed tampion in its open position, a barrel arm acted upon by a spring to overcome the weak spring and hold the tampion last mentioned in its closed position, means for rocking the said barrel arm to allow the lowest normally closed tampion to open when any of the higher note tampions are opened, and a lever moved when any lower note tampion is closed cooperating with said barrel arm to positively close the said lowest normally closed tampion. 70

3. A saxophone or like musical instrument comprising a series of key operated tampions for opening and closing vents corresponding to a group of successive notes of the chromatic scale arranged so that the tampions of the upper notes are normally closed and the tampions of the lower notes are normally open, a spring urged barrel arm which is rocked to allow the lowest normally closed tampion to open when any of the upper note tampions are opened, a key for thus rocking the said barrel arm independently of the opening of any upper note tampion, and a lever moved when any of the said lower note tampions is closed cooperating with said barrel arm to positively close the said lowest normally closed tampion. 75

4. A saxophone or like musical instrument comprising a series of key operated tampions for opening and closing vents corresponding to a group of successive notes of the chromatic scale arranged so that the tampions of the upper notes are normally closed and the tampions of the lower notes are normally open, a spring urged barrel arm which is rocked to allow the lowest normally closed tampion to open when any of the upper note tampions is opened, keys respectively arranged in the key groups actuated by different hands of the instrumentalist and effective for thus rocking the said barrel arm independently of the movement of any tampion of the said group of successive notes, and a lever moved when any of the said lower note tampions is closed to positively close the said lowest normally closed tampion. 80

5. A saxophone or like musical instrument comprising a series of key operated tampions for opening and closing vents corresponding to a group of successive notes of the chromatic scale arranged so that the tampions of the upper notes are normally closed and the tampions of the lower notes are normally open, a spring urged barrel arm which is rocked to allow the lowest normally closed tampion to open when any of the upper note tampions are opened, a lever moved when any of the lower note tampions is closed cooperating with said barrel arm to positively close the said lowest normally closed tampion, and keys respectively arranged one in each of the 85 90 95 100 105 110 115 120 125 130

key groups actuated by different hands of the instrumentalist and effective for closing one of the said normally open tampions.

6. A saxophone or like musical instrument comprising a series of key operated tampions for opening and closing vents corresponding to a group of successive notes of the chromatic scale arranged so that the tampions of the upper notes are normally closed and the tampions of the lower notes are normally open, key connections overlapped so that the opening of any upper note tampion alone effects simultaneously the opening of all the tampions below it down to and including the lowest normally closed tampion, a spring urged barrel arm by which the lowest normally closed tampion is moved to its closed position and a lever moved when any of the said lower note tampions is closed to positively close the said lowest normally closed tampion.

7. A saxophone or like musical instrument comprising a series of key operated tampions for opening and closing vents corresponding to a group of successive notes of the chromatic scale arranged so that the tampions of the upper notes are normally closed and the tampions of the lower notes are normally open, a weak spring for moving the lowest normally closed tampion to its open position, a barrel arm acted upon by a spring to hold the last mentioned tampion in its closed position, a key for rocking the barrel arm from its tampion closing position, and a lever moved when any lower note tampion is closed cooperating with said barrel arm to simultaneously close the lowest normally closed tampion against the action of the said weak spring.

8. A saxophone or like musical instrument comprising a series of key operated tampions for opening and closing vents corresponding to a group of successive notes of the chromatic scale arranged so that the tampions of the upper notes are normally closed and the tampions of the lower notes are normally open, a key connection for closing the first tampion below the lowest normally closed tampion when the second tampion below the lowest normally closed tampion is closed, a key connection for closing the first, second and third tampions below the lowest normally closed tampion when the fourth tampion below the lowest normally closed tampion is closed, a spring urged barrel arm which is rocked when any of the upper note tampions is opened to allow the lowest normally closed tampion to open and a lever moved when any of the lower note tampions is closed cooperating with said barrel arm to positively close the said lowest normally closed tampion.

9. A saxophone or like musical instrument comprising a series of key operated normally closed tampions corresponding to the notes top E $\flat$, E $\flat$ and D $\sharp$, overlapped key connec-

tions whereby the E $\flat$ and D $\sharp$ tampions are opened when the E $\flat$ tampion is opened and the D $\sharp$ tampion is opened when the E $\flat$ tampion is opened, a spring urged key operated barrel arm arranged to close the D tampion, and a lever whereby the tampion D $\sharp$ is positively closed independently of the opening of the E $\flat$ and E $\flat$ tampions when any of the normally open tampions top C $\sharp$ C $\flat$ B $\flat$ and B $\flat$ are closed.

10. A saxophone or like musical instrument comprising a series of key operated normally closed tampions corresponding to the notes top F $\sharp$ E $\flat$ E $\flat$ and D $\sharp$, overlapping key connections whereby opening of any of these tampions effects the opening of all the said tampions below it, a spring urged key operated barrel arm arranged to close the D $\sharp$ tampion and a lever whereby the tampion D $\sharp$ is positively closed independently of the opening of the tampions F $\sharp$ E $\flat$ and E $\flat$ when any of the normally open tampions top C $\sharp$ C $\flat$ B $\flat$ and B $\flat$ are closed.
